DOOR CONSTRUCTION

William D. Kelly, Western Springs, Ill., assignor
to Stewart-Warner Corporation, Chicago, Ill.,
a corporation of Virginia

Application January 23, 1939, Serial No. 252,330

6 Claims. (Cl. 20—16)

The present invention relates to a new and improved door construction and more particularly to a construction of means for guiding and controlling the opening and closing movement or 5 the like.

My invention may be used with any door construction but is particularly adapted for use with doors of stoves or refrigerators or other units having doors of considerable thickness. In such 10 units it is often desirable for reasons of design that the edges of adjacent doors be in close proximity. This may be desired merely for appearance or in order to provide a minimum of fixed structure between adjacent openings. One 15 specific application of the invention is in connection with a stove oven door which is located immediately above a grill door, the oven door swinging down from the top.

It is an object of the present invention to provide a new and improved door construction for 20 swinging doors.

It is a further object to provide a door supporting structure for controlling the swinging movement of doors with particular reference to 25 the movement of that edge of the door maintained adjacent the fixed structure to which the door is secured.

It is an additional object to provide a structure of this character adapted for use with doors 30 of substantial thickness used adjacent similar doors or set into the fixed structure.

It is also an object to provide a construction which is simple in design, composed of but few 35 parts and adapted for commercial production and use.

Other and further objects will appear as the description proceeds.

I have shown a preferred embodiment of my 40 invention in the accompanying drawings in which—

Figure 1 is a fragmentary vertical elevation showing the construction with the parts in closed position in full lines and in open position in broken lines;

Figure 2 is a plan view of the construction; and

Figure 3 is a vertical section taken on line 3—3 of Figure 1.

The supporting stove structure is shown generally at 11, and a lower door 12 is shown, this door being mounted in any suitable manner and closing a chamber below the oven which is closed by the door construction shown in detail herein. The oven door 13 is provided with the inner 55 wall 14 and the inturned edge 15 located adja-

cent the face 16 of the oven structure. The fixed guide or cam arm 17 is secured to the lateral edge wall 18 of the door by means of the machine screws 19. This arm has an arcuate portion 20 extending between the upper stop roller 5 21 and the lower guide roller 22, this arm being formed with upper and lower cam surfaces engaging the two rollers. The arm 17 is further provided with the hooked portion 23 adapted to engage the stop roller 21 with the parts in open 10 position as indicated in broken lines in Figure 1. The rear face of the hooked portion 23 of the arm 17 is provided with the opposed cam surfaces 24 and 25. These are adapted to engage the latch rollers 26. These rollers 26 are carried by the latch slide 27 which passes through the slide holder 28 and is held in position by pin 29 passing through the end of the member 27. The compression spring 30 is fitted around the member 27 and bears against the shoulder 31 so 15 as to normally thrust the latch rollers forwardly toward the door. The hook link 32 has a fixed pivot 33 upon the oven side wall and its opposite end is provided with the pivot 34 secured to the lateral edge wall 18 of the door at the point 25 adjacent its lower edge.

As best shown in Figures 2 and 3, the guide roller 22 is provided upon each side with the washers 35 and 36 so as to maintain the arm 17 in bearing relation upon the roller. The roller and washers are supported on the pivot 37 and are held in place by the U-pin 38 which is snapped into place in a groove in the supporting pivot. The stop roller 21 is also supported on a pivot 39 carried by the oven wall, and the roller is 35 held on the pivot by a U-pin 40 snapped upon the pivot. As will be apparent from Figures 2 and 3, the door is preferably provided with these guide arms and hook link connections at both 40 sides of the door. The parts are duplicates and the supporting pivots merely extend in opposite directions from the oven wall.

The position of the parts in the open and closed position is clearly shown in Figure 1. With the parts in the closed position, as shown in full 45 lines, when the upper edge of the door 13 is pulled to the left to open it, the arms 17, which are rigidly fixed to the door, move over the guide rollers 22 and this causes the door to lift, due to the fact that the lower edge of the arcuate 50 portion 20 of the arm 17 is not on a circular arc having the lower edge of the door for a center, but on a curve having centers spaced farther away from the arm than the lower edge of the door. As the door is swung forward, the 55

lower edge of the door rises and it is guided in its movement by the connection afforded by the hook links 32. These links, taken in connection with the bearing of the arm 17 on the guide roller 22, cause the lower edge to swing upwardly so that it fully clears the upper edge of the lower adjacent door 12. The stop roller 21 in addition to serving as a stop in the final open position, also prevents the arm 17 from lifting off the roller 22 in the earlier stages of the opening movement. The upper edge of the arcuate portion 20 of the arm 17 is formed upon a curve such as to maintain contact with the roller 21 throughout the opening and closing movement of the door.

It will be apparent that the first portion of the opening movement is resisted by the engagement of the latch roller 26 against the cam surface 24. The roller rises on this cam, however, compressing the spring 30, and as the roller passes over the point between cam surfaces 24 and 25, the door is released for free opening movement. When the door is swung in the reverse direction the parts take a reverse movement, the arms 17 being guided by the rollers 21 and 22. As the door approaches closed position the cam surface 25 thrusts the latch rollers 26 against the springs 30 and the springs are compressed until the rollers 26 pass over against the cam surface 24, when compression is only partially released so that the springs and rollers serve to hold the door firmly in closed position.

The combined swinging and lifting movement imparted to the lower edge of the door by its linked connection to the oven permits this lower edge to be located closely adjacent other portions of the stove which project outwardly as far as the outer face of the door. The adjacent portions may be a similar door to a broiler or warming oven or the like, or may be a fixed portion of the stove construction. It will be understood that the doors of modern types of stoves are of substantial thickness to permit of the door being provided with insulation.

While I have shown one preferred form of construction by way of example, the device may be modified to meet varying conditions and requirements and I contemplate such changes and variations as come within the spirit and scope of the appended claims.

I claim:

1. Support construction for swinging doors comprising a link pivotally connected to the door adjacent one edge thereof and connected to fixed door supporting structure, a guide arm rigidly connected to an intermediate portion of the door, and guide means associated with the lower side of the arm for lifting movement of the arm and door during the opening of the door.

2. Support construction for swinging doors comprising a link pivotally connected to the door adjacent one edge thereof and connected to fixed door supporting structure, a guide arm rigidly connected to an intermediate portion of the door 5 said arm having cam portions on the lower side thereof, and guide means associated with the cam portions of the arm for lifting movement of the arm and door during the opening of the door.

3. Support construction for swinging doors 10 comprising a link pivotally connected to the door adjacent one edge thereof and connected to fixed door supporting structure, a guide arm rigidly connected to an intermediate portion of the door, cam surfaces upon upper and lower edges of the 15 arm, and fixed guide means engaging said cam surfaces for lifting and limiting movement of the door during the opening of the door.

4. Support construction for swinging doors 20 of substantial thickness, comprising a link pivotally connected at one end to the door at a point adjacent but spaced from an edge and the inner face of the door and connected at the other end to fixed door supporting structure, a guide arm rigidly connected to an intermediate portion 25 of the door, and guide means associated with the arm for guiding movement of the arm and door to cause the edge of the door adjacent the link connection to have a lifting and swinging movement.

5. Support construction for swinging doors of substantial thickness, comprising a link pivotally connected at one end to the door at a point adjacent but spaced from an edge and the inner face of the door and connected at the other end 35 to fixed door supporting structure, a guide arm rigidly connected to an intermediate portion of the door, said arm having upper and lower cam surfaces, and guide rollers associated with the arm engaging the upper and lower cam surfaces 40 for guiding movement of the arm and door to cause the edge of the door adjacent the link connection to have a lifting and swinging movement.

6. Support construction for swinging doors of substantial thickness, comprising a link pivotally 45 connected at one end to the door at a point adjacent but spaced from an edge and the inner face of the door and connected at the other end to fixed door supporting structure, a guide arm rigidly connected to an intermediate portion of 50 the door, oppositely inclined cam surfaces on the free end of the arm, spring latch means engaging said surfaces, and guide means associated with the arm for guiding movement of the arm and door to cause the edge of the door adjacent 55 the link connection to have a lifting and swinging movement.

WILLIAM D. KELLY.
